UNITED STATES PATENT OFFICE.

WILLIAM F. YAXLEY, OF CHICAGO, ILLINOIS.

CALCULATING-MACHINE.

SPECIFICATION forming part of Letters Patent No. 767,468, dated August 16, 1904.

Application filed November 2, 1903. Serial No. 179,625. (No model.)

To all whom it may concern:

Be it known that I, WILLIAM F. YAXLEY, residing at Chicago, Cook county, Illinois, have invented certain new and useful Improvements in Calculating-Machines, of which the following is a specification.

My invention relates to calculating-machines having a series of key-controlled wheels or dials by which amounts corresponding to the value of the key or keys operated are registered and totalized; and the object of my invention is to provide a simple and inexpensive machine of this character embodying new constructions and principles of operation, as will be apparent from the description hereinafter given.

In the drawings, Figure 1 is a plan view of my machine; Fig. 2, an end elevation thereof; Fig. 3, a plan view of the machine with the top of the casing broken away; Fig. 4, a section on line 4 of Fig. 3; Fig. 5, a detail view of the carry-one mechanism; Fig. 6, a section on line 6 of Fig. 4; Fig. 7, a diagrammatic view showing another differential in distance between the lugs on the operating rod or bar and between the operating-levers, respectively; and Fig. 8, a detail view of the modified form of construction of the operating rod or bar.

The operating parts of my machine, with the exception of the key-buttons, are inclosed in the present instance in a suitable casing comprising a base 10, end walls 11, front wall 12, rear wall 13, and top 14. Upon the base are supported standards 15, to which is secured a main shaft 16, extending transversely of the machine and constituting the axis for a series of adding-wheels 17, which are loosely mounted on such shaft. These wheels, which indicate units, tens, hundreds, thousands, and so on, are each provided on their right-hand side or face with a ratchet-wheel 18, whereby such wheels 17 are actuated in the manner hereinafter described. These adding-wheels may be of any number according to the desired capacity of the machine, and in the present instance I have shown a series of eight of these wheels, so that the machine is capable of registering up to one hundred millions. Sight-openings 14^a are provided in the top of

the casing to expose the indications on the adding-wheels. Each of the adding-wheels is provided on its periphery with four series of figures, from "0" to "9," although any number of such series may be employed; but the number shown is considered preferable for the reason that the extent of movement of the parts for actuating the wheels is lessened. The ratchet-wheels 18 are provided with marginal teeth corresponding in number with the figures on the adding-wheels.

The mechanism for actuating the adding-wheels comprises a series of lever-arms 19, corresponding in number to said wheels and pivoted loosely upon the main shaft. These lever-arms have hub portions formed into segmental gear-wheels 20 and are provided at their outer ends with pivoted spring-pressed pawls 21, adapted to engage the ratchet-wheels 18, and thereby actuate and rotate the adding-wheels a distance corresponding to the amount of movement or throw of the lever-arms.

A second shaft 22 is mounted between the standards 15 and arranged in front of the adding-wheels. Similar operating-levers 23, equal in number to the adding-wheels, are pivoted intermediate of their length to this shaft and terminate at their rearward ends in geared segments 24, adapted to engage the segmental gear-wheels 20, hereinbefore described, whereby the movement of any one of the operating-levers 23 is communicated to its adding-wheel. The forward ends of these levers are drawn upward by means of suitable springs, as the springs 25, with the result that the actuating-levers 19 are normally held against stops 26, arranged on the top of the casing, as shown in Fig. 4.

A vertically-swinging bail comprising arms 27 and cross-bar 28 is pivoted to the shaft 22 near its ends and yieldingly held in a normal horizontal position by means of a spring 29, as shown in Fig. 4. The parallel arms 27 of the bail are provided with slots through which passes a bar 30, capable of sliding but prevented from rotating with respect to the bail by reason of the angular construction of the bar and slots. This sliding bar is provided on its rear edge with a series of projecting

lugs 31, one for each lever-arm 19, and so arranged with respect to these lever-arms that only one of the lugs will engage a lever at a time when the bail swings downwardly, while 5 the other lugs will be permitted to pass by. To accomplish this result, the distance between the lugs is differential with respect to the distance between the levers, and in the present instance this differential is expressed by the 10 ratio 7 to 8; but any other ratio may be adopted so long as the stated purpose is effected. Referring to Fig. 3, the sliding bar is in such 15 position that its first lug on the right will contact and actuate the lever of the units-wheel when said bail is depressed, while all the other lugs will clear their respective levers. When 20 the bail and also the sliding bar carried thereby are swung downwardly while the parts are in the relative position indicated in Fig. 3, the first lug on the right—that is, the units-lug—will contact, and consequently actuate 25 the lever-arm of the units-wheel a certain distance, according to the value of the key depressed, as hereinafter explained. When the bar is moved one unit of space to the left in a manner to be described, the second lug from the right-hand end—that is, the tens-lug—will be brought into operative relation with the tens-lever—that is, the lever of the tens-wheel—while all the other lugs, including the 30 units-lug, theretofore in operative relation with the units-lever, will be in a position to pass by or clear their respective levers whenever the bail is depressed. Consequently at this time 35 the tens-wheel alone will be actuated. Further shifting of the sliding bar to the left a space at a time with respect to the bail which supports it will bring the other lugs into operative relation with their respective levers, so 40 that any one of the operating-levers is capable of being actuated by the sliding bar, whose position is controlled by the operator. The extreme movement of such bar to the left will bring the last-lug on the left into operative relation with the lever of the last wheel on the left. According to the construction shown when 45 the bar has been shifted to this extreme position just described the units-lug is brought into the same vertical plane as the tens-lever, and to avoid contact and actuation of such tens-lever under these circumstances the tens-lug is made longer than the others and its tens-lever is made correspondingly shorter, with the result that such units-lug will clear 50 the end of this shortened tens-lever when in the same vertical plane as the latter, and the last lug on the left will then be the only one to contact a lever-arm when the bail is depressed. In this manner the eight lugs are 55 capable of operating the eight levers; but the operation is permitted of only one lug at a time.

In order to give the sliding bar a step-by-step movement and enable it to be shifted a 60 proper distance or space, I provide the same

with an escapement comprising a pawl 32, which co-operates with a series of ratchet-teeth 33 on the under side of the sliding bar, whereby the bar is held in set or adjusted positions against the tension of a spring 34, tending to draw the bar to the left. This pawl, which is pivoted at 35 to the cross-bar of the bail, is provided at its opposite ends with teeth 36 37, adapted to alternately engage the ratchet-teeth. The distance between these ratchet-teeth bears such a relation to the distance between the lugs of the bar that the escapement will permit the said spring 34 to shift the bar sufficiently to draw one lug from operative relation with its lever and bring the next lug 80 into operative relation with its lever. The pawl of the escapement is spring-pressed as to its right-hand end, Fig. 6, in suitable manner, as by a coiled spring 38, which tends to hold the tooth 37 in engagement with the 85 ratchet-teeth 33. The right-hand end of the pawl is provided with a pin 39, extending to the front of the machine, as shown in Figs. 3 and 4, in the range of operating mechanism now to be described.

A shifting rod 40 is arranged to slide transversely of the machine in bearings 41, formed in standards 42, secured to the base of the casing. This rod is capable of sliding longitudinally, but prevented from rotating. An operating-handle or sliding key 42, projecting through a horizontal slot in the front wall of the casing, is secured to the rod, whereby such rod may be shifted laterally to the right against the force of a spring 43, tending to thrust the rod to the left. The rod 40 is provided on its inner or rearward side with a short pin 44, located at such a point intermediate of the length of the rod that when the operating parts are in their normal position such pin 105 will contact and engage the pin 39, extending from the pawl of the escapement, as hereinbefore described, with the result that the pawl is prevented during such contact from acting freely by reason of the depression of its right-hand end against the tension of the spring 38. A movement of this rod to the right by the operator removes the short pin 44 from such contact with the pawl-pin 39 and enables such pawl to work freely for the purposes hereinafter made apparent. The rod is restored to normal position by its spring 43. The left-hand end of the rod 40 is provided with an arm 45, extending inwardly—that is, toward the rear of the machine—and in the same horizontal plane as the sliding bar in order to move such bar to the right when the rod 40 is moved in the same direction, as described. Before contacting the bar the arm 45 has a slight movement sufficient to disengage the 115 pins 39 and 44 and permit the pawl to act freely when the bar is moved to the right, at which time the pawl will trip over the ratchet-teeth.

In the left-hand corner of the machine-cas- 120

ing next to the operator is a wedge 46, which is arranged to slide in suitable grooves and connected to a push key or lever 47, passing through the top of the casing. This wedge 5 is adapted to be moved or shifted by this push-key against the left-hand end of the sliding rod 41, with the result that such rod will be slightly moved to the right, but sufficiently to cause disengagement of the two 10 pins 39 and 44 for a purpose hereinafter made apparent when the operation of the machine is described.

Ten operating-keys 48 are provided, the same being numbered "0" to "9," both inclusive, which numbers represent the value of the respective keys. These keys have vertical stems or rods 49, which bear in and are guided by a series of openings in two horizontal cross-bars 50 in the standards 42. 20 These keys are normally upwardly spring-pressed by the coiled springs 51. Suitable means are employed for giving each key an amount of depression corresponding to its value. For instance, the No. 1 key has a certain or unit amount of depression, while key No. 2 has twice that amount of depression, and so on. In the present instance I accomplish this result by providing a series of step-by-step stops 52, arranged on the base of the 25 machine and immediately below the lower ends of the key-rods, whose downward movement is thereby limited. The highest step is immediately below the cipher-key and the lowest step below the No. 9 key. Each key-rod or step has a pin 53 extending toward the rear of the machine and normally above or in contact with the upper edge of the cross-bar of the swinging bail, with the result that 30 a depression of any one of the operating-keys 40 will swing the bail downward a distance corresponding to the value of the key 50 operated.

The carrying device comprises in the present instance a series of levers 54 and pawls 55, operatively connecting the indicating-wheels for the purpose of carrying one from one wheel to the next. These levers 54 are arranged below and at one side of their respective wheels, (with the exception of the last 50 wheel on the left, which obviously needs no carrying-lever,) the same being pivoted intermediate their length on short standards 56 to permit the levers to swing in a vertical plane. The rear end of each lever is turned 55 upward to form a wedge or triangular-shaped tooth 57, which is adapted to be contacted and moved by any one of a series of pins 58. All the wheels with the exception of the last one on the left are provided with one of these 60 pins for each series of figures thereon, and as such wheels in the present instance have four series they are each provided with four pins 58, spaced equidistantly on the left-hand face thereof near the periphery and in position to 65 contact and actuate the levers. An arm 54^a

projects laterally to the left from the forward end of each lever 54, and upon the free end of such arm is pivoted the long vertically-extending pawl 55, which engages the ratchet-teeth of the indicating-wheel next to the left 70 of the one with which its lever 54 directly cooperates. Depression of the rear end of any one of the levers 54 by one of the pins 58 will depress such end of the lever and rock the other end and the pawl upward, with the 75 result that the wheel with which the pawl cooperates is advanced one space or number. Besides acting to operate the wheels, as described, these pawls also serve as detent-pawls to keep the wheels from overthrowing. 80 The amount of rocking of these levers may be adjusted to a nicety by a series of adjusting-screws 59, screwing into short posts 60.

In practice the adding-wheels are first brought to zero position and the sliding key 85 42, together with its rod 41, moved to the right, with the result that the sliding bar is also shifted to its right-hand position, the escapement permitting such shifting at this time owing to the fact that the pins 39 and 44 are 90 now disengaged. When the sliding key is released, such key and rod are restored to normal position by the spring 43 and the pins 39 and 44 are again in engagement. The machine is now set ready for the calculating operation. To clearly describe the operation, we will take, as an example, the addition of the two numbers "786" and "402." The first number is indicated on the machine by depressing the "6" key, which will swing the 100 bail as well as the sliding bar downward six spaces. As the first lug on the right—that is, the units-lug—is now in operative relation with the units-lever, the units-wheel will be moved such a distance as to expose a "6" 105 through the sight-opening. During this downward movement of the bar all the other lugs pass freely on one side of their respective operating-levers. After the key "6" is released the bail, bar, and units-lever are all 110 restored to normal position by their respective springs. When the bail returns to normal position, as described, the pin 39 of the escapement is brought into contact with the pin 44 on the bar 40, with the result that the 115 pawl will permit a movement of the sliding bar a distance of one tooth, which is one-half the distance required to bring the next or tens lug in operative relation with its operating-lever. The "8" key is next depressed, whereupon the first movement will cause disengagement of the pins 39 and 44 and allow the pawl to trip the ratchet another tooth, thereby permitting the sliding bar to move to the left another space and bring the tens-lug in position 120 to operate the tens-lever. Further movement causes the tens-lug to thus actuate the tens-lever and indicate "8" on the tens-wheel. The actuating parts are restored as before and the sliding bar shifted a single space to the 125 130

left. The "7" key is now depressed, and the hundreds-lug on the sliding bar is caused to actuate the hundreds lever and wheel, with the result that the number "786" is now indicated on the machine. It being desired to add "402" to "786," as hereinbefore suggested, the machine is reset by operating the sliding key 42 in the manner already explained. The "2" key is now depressed, and the units-wheel is turned so as to expose the figure "8" through the sight-opening. As the next figure in the number to be added is a cipher, the depression of the "0" key will simply move the swinging bail sufficiently to operate the escapement and shift the sliding bar a single space, as already made apparent, but without affecting the tens-wheel. The "4" key is now depressed, whereupon the sliding bar is first moved another space, so as to bring the hundreds-lug into operative relation with its lever and transfer the value of the key so depressed to the hundreds-wheel. As the addition of "4" upon the hundreds-wheel will move such wheel beyond its "9," the carry-one mechanism is brought into operation, for after the figure "9" has passed the sight-opening one of the pins 58 of the hundreds-wheel will contact the tooth 57 of the lever 54 belonging to that wheel, and thereby cause its long pawl 55 to move upward a distance of one tooth and advance the thousands-wheel one figure, so that the thousands-wheel will now expose "1" through the sight-opening. The hundreds-wheel after having passed the "9," as stated, continues until the figure "1" of the next series or set of figures appears through its sight-opening, whereupon the machine indicates "1188" as the result of the addition. The addition of other numbers is performed in the same manner, the total always appearing plainly through the sight-openings. The wheels are set to zero position by pushing the sliding key 42 to its limit of stroke to the right and then commencing with the units-wheel by adding sufficient thereto in the manner above described to make ten, whereupon "0" will appear through the sight-opening. This operation should be repeated until all the wheels show "0."

For the purpose of adding a column of one denomination of figures or the repeated addition of the same figure in one denomination, as in multiplication, the key or lever 47 is pulled outwardly, thereby causing the wedge 46 to shift the rod 40 and release the pawl of the escapement, with the result that the same lug can repeatedly actuate the same lever and wheel. Any one of the wheels can be thus operated repeatedly by bringing its lug in cooperative relation with its lever by depression of the "0" key the required number of times.

By the use of my machine a column of figures may be totalized by a series of simple and rapid operations. Moreover, my ma-

chine is comparatively simple in its construction and operation considering its capacity.

The differential in distance between the lugs and the operating-levers may be varied so long as the intended operation follows, and in order to show a variation in such differential I have illustrated the bar and ends of the operating-levers in a diagrammatic way, the lugs being spaced or separated by distances corresponding to the numbers or ratios 7, 6, 5, 4, 5, 6, and 7 and the levers by the numbers or ratios 8, 7, 6, 5, 6, 7, and 8. Again, the bar or rod for actuating the operating-levers may partake of a different construction, and instead of moving or sliding laterally in order to present the proper lug the bar or rod may be made to rock or rotate with the same results. In Fig. 8 I have shown such modification, in which the rod or bar 61 is provided with a series of lugs 62, properly arranged and spaced in spiral fashion on the periphery of such bar, and is also provided with an escapement-wheel 63, operated in any suitable manner.

I claim—

1. A calculating-machine comprising a series of adding-wheels, operating-keys, and mechanism intermediate the keys and wheels consisting of levers for operating the wheels, and a bodily sliding and swinging bar arranged to be depressed by any one of the keys and to operate the lever of any one of the wheels according to the relative position of the bar.

2. A calculating-machine comprising a series of adding-wheels, operating-keys, and mechanism intermediate the keys and wheels consisting of levers for operating the wheels, and a sliding and swinging bar having a series of lugs and arranged to be depressed by any one of the keys and to operate the lever of any one of the wheels through contact between such lever and one of the lugs as predetermined by the operator.

3. A calculating-machine comprising a series of adding-wheels, operating-keys, and mechanism intermediate the keys and wheels consisting of levers for operating the wheels, and a sliding and swinging bar having a series of lugs which are spaced differentially as respects the spacing or distance between said levers for operating the wheels, said bar being arranged to be depressed by any one of the keys and to operate the lever of any one of the wheels through contact between such lever and one of the lugs as predetermined by the operator.

4. A calculating-machine comprising a series of adding-wheels, operating-keys, and mechanism intermediate the keys and wheels consisting of levers for operating the wheels, a sliding and swinging bar arranged to be depressed or swung by the keys and having a series of means of engagement with the wheel-levers one at a time, and means for moving or sliding said bar longitudinally.

5. A calculating-machine comprising a series of adding-wheels, operating-keys, and mechanism intermediate the keys and wheels consisting of levers for operating the wheels, a sliding and swinging bar arranged to be depressed or swung by any one of the keys and having a series of lugs arranged to operate the levers one at a time, and means for moving or shifting the bar to bring the lugs into successive engagement with the levers. 5
6. A calculating-machine comprising a series of adding-wheels, operating-keys, and mechanism intermediate the keys and wheels consisting of levers for operating the wheels, a sliding and swinging bar arranged to be depressed or swung by any one of the keys and having a series of lugs spaced differentially as respects the spacing or distance between said levers for operating the wheels, and means for moving or shifting the bar to bring the lugs into successive engagement with the levers. 15
7. A calculating-machine comprising a series of adding-wheels, operating-keys, and mechanism intermediate the keys and wheels consisting of levers for operating the wheels, and a swinging bar arranged to be swung by any one of the keys and having on one edge adjacent the wheel-levers a series of lugs adapted to engage such levers one at a time. 25
8. A calculating-machine comprising a series of adding-wheels, operating-keys, and mechanism intermediate the keys and wheels consisting of levers for operating the wheels, a swinging bar arranged to be swung by any one of the keys and having on one edge adjacent the wheel-levers a series of lugs adapted to engage such levers one at a time, and means for shifting such bar longitudinally to present the lugs successively to their respective levers for operating the latter when any one of the keys having a valve is depressed. 35
9. A calculating-machine comprising a series of adding-wheels, operating-keys, and mechanism intermediate the keys and wheels consisting of levers for operating the wheels, a swinging bar arranged to be swung by any one of the keys and having on one edge adjacent the wheel-levers a series of projecting lugs, one for each wheel-lever, and arranged to engage such levers one at a time, and means for shifting such bar longitudinally to present the lugs successively to their respective levers for operating the latter. 45
10. A calculating-machine comprising a series of adding-wheels, operating-keys, and mechanism intermediate the keys and wheels consisting of levers for operating the wheels, a swinging bar arranged to be swung by any one of the keys and having on one edge adjacent the wheel-levers a series of projecting lugs, one for each wheel-lever, all said lugs being of the same length except the lugs for the units and tens levers, which two lugs are respectively shorter and longer than the others, said levers being of the same length except the units and tens levers, which are respectively longer and shorter than the others. 55
11. A calculating-machine comprising a series of adding-wheels, operating-keys, and mechanism intermediate the keys and wheels consisting of levers for operating the wheels, a bodily-swinging bail arranged to be actuated by the keys, and a bar carried by such bail and having means for engagement with the wheel-operating levers one at a time. 70
12. A calculating-machine comprising a series of adding-wheels, operating-keys, and mechanism intermediate the keys and wheels consisting of levers for operating the wheels, a bodily-swinging bail arranged to be actuated by the keys, and a bar carried by such bail and capable of longitudinal movement therein, said bar having means for engagement with the levers one at a time. 80
13. A calculating-machine comprising a series of adding-wheels, operating-keys, and mechanism intermediate the keys and wheels consisting of levers for operating the wheels, a swinging bail arranged to be actuated by the keys, and a bar mounted on the parallel arms of the bail and adapted to slide longitudinally therein, said bar having a series of means for engagement with the levers one at a time. 85
14. A calculating-machine comprising a series of adding-wheels, operating-keys, and mechanism intermediate the keys and wheels consisting of levers for operating the wheels, a swinging bail arranged to be actuated by the keys, and a bar carried by such bail and capable of longitudinal movement therein but prevented from turning axially, said bar having a series of means for engagement with the levers one at a time. 90
15. A calculating-machine comprising a series of adding-wheels, operating-keys, and mechanism intermediate the keys and wheels consisting of levers for operating the wheels, a swinging bail arranged to be actuated by the keys and having slots in its parallel arms, and a bar slidably in such slots and having means for engagement with the levers one at a time. 105
16. A calculating-machine comprising a series of adding-wheels, operating-keys, and mechanism intermediate the keys and wheels consisting of levers for operating the wheels, a swinging bail arranged to be actuated by the keys, a bar carried by such bail and capable of longitudinal movement with respect thereto, said bar having means for engagement with the levers one at a time, and an escape- 110
ment for permitting the bar to be moved or shifted longitudinally - predetermined distances. 120
17. A calculating-machine comprising a series of adding-wheels, operating-keys, and mechanism intermediate the keys and wheels consisting of levers for operating the wheels, 130

- a bodily-swinging bail arranged to be actuated by the keys, a bar carried by such bail and capable of longitudinal movement with respect thereto, such bar having means for engagement with the levers one at a time, a spring tending to draw the bar in one direction, and an escapement for permitting the bar to be shifted by its spring a space at a time.
18. A calculating-machine comprising a series of adding-wheels, operating-keys, and mechanism intermediate the keys and wheels consisting of levers for operating the wheels, a bodily-swinging bail arranged to be actuated by the keys, a bar carried by such bail and capable of longitudinal movement with respect thereto, such bar having means for engagement with the levers one at a time, a spring tending to draw the bar in one direction, and an escapement controlled by the movements of the bail for permitting the bar to be shifted by its spring a space at a time.
19. A calculating-machine comprising a series of adding-wheels, operating-keys, and mechanism intermediate the keys and wheels consisting of levers for operating the wheels, a bodily sliding and swinging bar arranged to be depressed or swung by the keys and having means of engagement with the wheel-levers one at a time, means for permitting a step-by-step movement of such bar, and manually-operated means for sliding such bar longitudinally.
20. A calculating-machine comprising a series of adding-wheels, operating-keys, and mechanism intermediate the keys and wheels consisting of levers for operating the wheels, a sliding and swinging bar arranged to be depressed or swung by the keys and having means of engagement with the wheel-levers one at a time, means for permitting a step-by-step movement of such bar, and a manually-operated sliding rod having a projecting arm arranged in the path of movement of the bar for restoring the latter to normal position.
21. A calculating-machine comprising a series of adding-wheels, operating-keys, and mechanism intermediate the keys and wheels consisting of levers for operating the wheels, a swinging bail arranged to be actuated by the keys, a bar carried by such bail and capable of longitudinal movement in respect thereto, said bar having means for engagement with the levers one at a time, an escapement co-operating with the bar to permit step-by-step movement thereof in one direction, and a sliding rod arranged to restore the bar to normal position and having a projecting pin co-operating with the escapement to permit operation of the latter when a key is depressed and the bail swung.
22. A calculating-machine comprising a series of adding-wheels, operating-keys, and mechanism intermediate the keys and wheels consisting of levers for operating the wheels, a swinging bail arranged to be actuated by the keys, a bar carried by such bail and capable of longitudinal movement in respect thereto, said bar having means for engagement with the levers one at a time, an escapement co-operating with the bar to permit step-by-step movement thereof in one direction, such escapement comprising ratchet-teeth on the bar, a spring-pressed pawl pivoted on the bail and adapted to engage the teeth, and a pin projecting from the spring-pressed end of the pawl, and a sliding rod arranged to restore the bar to normal position and having a pin arranged to engage the pawl-pin and normally hold one end of the pawl from engagement with the ratchet-teeth.
23. A calculating-machine comprising a series of adding-wheels, operating-keys, and mechanism intermediate the keys and wheels consisting of levers for operating the wheels, means for permitting the operating-keys to be depressed different distances according to their respective values, a swinging bail arranged to be actuated different distances according to the value of the key operated, a bar carried by such bail and capable of longitudinal movement, said bar having means for engagement with the levers one at a time, and an escapement co-operating with the bar and controlled by the swinging movements of the bail for permitting a step-by-step movement of the bar.
24. A calculating-machine comprising a series of adding-wheels, operating-keys, and mechanism intermediate the keys and wheels consisting of levers for operating the wheels, and an escapement-controlled rod or bar arranged to be depressed by any one of the keys and to operate the lever of any one of the wheels according to the relative position of the bar.
25. A calculating-machine comprising a series of adding-wheels, operating-keys, and mechanism intermediate the keys and wheels consisting of levers for operating the wheels, and an escapement-controlled rod or bar having a series of lugs and arranged to be depressed by any one of the keys and to operate the lever of any one of the wheels through contact between such lever and one of the lugs as predetermined by the operator.
26. A calculating-machine comprising a series of adding-wheels, operating-keys, and mechanism intermediate the keys and wheels consisting of a bodily-movable escapement-controlled rod or bar operated by the keys, and operating connections between the rod or bar and the adding-wheels.
27. A calculating-machine comprising a series of adding-wheels, operating-keys, and mechanism intermediate the keys and wheels consisting of a bodily-movable escapement-controlled rod or bar operated by the keys, and levers actuated by the rod or bar for op-

erating the adding-wheels in a direction opposite the said levers.

28. A calculating-machine comprising a series of adding-wheels, operating-keys, and mechanism intermediate the keys and wheels consisting of an escapement-controlled rod or bar arranged to bodily swing and also to slide and adapted to be actuated by any one of the keys.

10 29. A calculating-machine comprising a series of adding-wheels, operating-keys, and mechanism intermediate the keys and wheels consisting of levers for operating the wheels and a bodily sliding and swinging rod or bar 15 arranged to be swung by any one of the keys and to operate the lever of any one of the wheels.

30. A calculating-machine comprising a series of adding-wheels, operating-keys, and mechanism intermediate the keys and wheels 20 consisting of levers for operating the wheels, and a movable bar having a series of lugs and arranged to operate the lever of any one of the wheels through contact between such lever 25 and one of the lugs as predetermined by the operator.

31. A calculating-machine comprising a series of adding-wheels, operating-keys, and mechanism intermediate the keys and wheels 30 consisting of levers for operating the wheels in a direction opposite that of the levers, a swinging bail arranged to be actuated by the keys, and an escapement-controlled bar carried by such bail and having means for engagement with the wheel-operating levers one 35 at a time.

32. A calculating-machine comprising a se-

ries of adding-wheels, operating-keys, and mechanism intermediate the keys and wheels consisting of a swinging bar operated by the 40 keys, and operating connections between the bar and the adding-wheels, said bar being arranged to actuate said connections at different points along its length.

33. A calculating-machine comprising a series of adding-wheels, operating-keys, and mechanism intermediate the keys and wheels 45 consisting of an escapement-controlled bar operated by the keys, and operating connections between the bar and the adding-wheels, said 50 bar being arranged to actuate said connections at different points along its length.

34. A calculating-machine comprising a series of adding-wheels, operating-keys, and mechanism intermediate the keys and wheels 55 consisting of levers for operating the wheels, and a sliding bar arranged to swing in a plane at right angles to its length and to operate the lever of any one of the wheels according 60 to the relative position of the bar.

35. A calculating-machine comprising a series of adding-wheels, operating-keys, and mechanism intermediate the keys and wheels consisting of levers for operating the wheels, and a sliding bar extending substantially the 65 width of the series of adding-wheels and arranged to swing and thereby operate the lever of any one of the wheels according to the relative position of the bar.

WILLIAM F. YAXLEY.
